(57) **CLAIM**

The ornamental design for a container for liquid pharmaceutical product as shown.

DESCRIPTION

FIG. 1 is a bottom view of the container for liquid pharmaceutical product of the present invention;

FIG. 2 is a front view of the container for liquid pharmaceutical product with the liquid-holding member rotated; FIG. 3 is a front view of the container for liquid pharmaceutical product;

FIG. 4 is a left side view of the container for liquid pharmaceutical product with the liquid-holding member rotated; FIG. 5 is a left side view of the container for liquid pharmaceutical product;

FIG. 6 is a perspective view of the container for liquid pharmaceutical product with the liquid-holding member rotated; FIG. 7 is a perspective view of the container for liquid pharmaceutical product; and,

FIG. 8 is a top view of the container for liquid pharmaceutical product.

1 Claim, 4 Drawing Sheets
